CLAIM

The ornamental design for a pickup truck rear bucket storage drawer, as shown and described.

DESCRIPTION

FIG. 1 is a perspective front view of a pickup truck rear bucket storage drawer showing my new design;

FIG. 2 is a perspective back view thereof;

FIG. 3 is a front view thereof;

FIG. 4 is a back view thereof;

FIG. 5 is a right-side view thereof;

FIG. 6 is a left-side view thereof;

FIG. 7 is a top view thereof;

FIG. 8 is a bottom view thereof;

FIG. 9 is a magnified view of a top portion of the front side thereof; and,

FIG. 10 is a magnified view of a middle portion of the back side thereof.

The dash-dash broken lines illustrate portions of the pickup truck rear bucket storage drawer that form no part of the claimed design. The dot-dash broken lines illustrate the periphery of the enlarged views of the pickup truck rear bucket storage drawer and form no part of the claimed design.

1 Claim, 10 Drawing Sheets
